Design No. 13,438, dated November 21, 1882.

1

UNITED STATES PATENT OFFICE.

HENRY BOSSHARDT, OF NEW YORK, N. Y., ASSIGNOR TO THE KURSHEEDT MANUFACTURING COMPANY, OF SAME PLACE.

DESIGN FOR EMBROIDERY.

SPECIFICATION forming part of Design No. 13,438, dated November 21, 1882.

Application filed September 28, 1882. Term of patent 7 years.

To all whom it may concern:

Be it known that I, HENRY BOSSHARDT, of New York, in the county and State of New York, have invented a new and original Design for an Embroidery, of which the following is a specification.

The accompanying photograph represents a face view of my new embroidery.

This invention relates to a new embroidery representing a crane; and it consists of the new configuration and arrangement of the parts of which the representation of the bird is made up.

In the photograph the letter A represents the head of the bird; B, the body thereof, and C the legs. The head carries representations of radiating crown-feathers *a*, and around and above these representations of a series of outer crown-feathers, *b*. The upper part of the head is represented by a stripe, *c*, from which the stripes *d*, forming the back of the head, extend. The bill *e* is made of two stripes of embroidery-threads. The neck *l* connects the head A with the body B, and from its lower part diverge series of representations of feathers *f*, which enter partially into the composition of the body. The

body B itself shows the representation of a series of covering-feathers, *g*, overlapping partly the representation of the wing *h*, which in turn overlaps the representation of the tail *i*. The lower part of the body shows representations *j* of the belly-feathers, and from it extend downward the legs C, one of which is straight, the other bent, as shown. The whole arrangement of these representations of feathers produces a peculiar new effect. The feathers themselves are composed of oblique embroidery-threads that traverse them from one edge to the other; but in this application I do not claim that feature of my invention, because it is already claimed in another application filed at the same time with this, and marked "application A."

I claim—

The design for an embroidery, the same consisting of the representation of a bird, having the parts *a*, *b*, *c*, *d*, *e*, *l*, *f*, *g*, *h*, *i*, *j*, and C, substantially as shown.

HENRY BOSSHARDT.
